UNITED STATES PATENT OFFICE.

EUGENE ALBERT PALMER, OF BELLE PLAINE, IOWA.

WASHING-MACHINE.

1,097,664.

Specification of Letters Patent.

Patented May 26, 1914.

Application filed September 27, 1911. Serial No. 651,666.

To all whom it may concern:

Be it known that I, EUGENE ALBERT PALMER, a citizen of the United States, residing at Belle Plaine, in the county of Benton 5 and State of Iowa, have invented a new and useful Washing-Machine; and I do hereby declare the following to be a full, clear, and exact description of the invention, such as will enable others skilled in the art to which 10 it appertains to make and use the same.

This invention relates to a new and useful washing machine.

The principal object of the invention is the provision of an improved washing machine provided with a novel form of pendulum clothes agitator or pounder.

The invention comprises further features and combination of parts, as hereinafter set forth, shown in the drawings and claimed.

20 In the drawings:—Figure 1 is a view in perspective of a washing machine constructed in accordance with the invention. Fig. 2 is a longitudinal sectional view. Fig. 3 is a perspective view of the agitator. Fig. 4 is a sectional view of the agitator taken longitudinally therethrough. Fig. 5 is a transverse sectional view of the agitator. Fig. 6 is a detail sectional view showing the connection of one of the hangers to the shaft 11.

30 Referring more especially to the annexed illustrations 1 designates a suitable receptacle for the clothes and the suds, the same being supported by suitable legs 2, and provided with a hinged closure 3, which is held 35 closed by the latch 4.

The side of the receptacle is provided with an aperture 6, to receive a plug 7, which may be withdrawn to empty the suds of the receptacle.

40 Extending transversely of the receptacle, and spaced apart from the bottom thereof, and adjacent each end are transverse strips or cleats 9, against which the clothes are rubbed or agitated.

45 The closure is in the form of a basin, and when the same is closed the basin is inverted, but when open the same acts as means to catch the drippings from the agitator or pounder. Extending transversely of the side 50 of the closure or basin is a rock shaft 11, one end of which terminates in a right angled extending arm 11^a, which terminates in a handle 14, whereby the shaft 11 may be rocked. Suspended from the shaft by means 55 of the hangers 13^a is a pendulum agitator or pounder 13. The lower ends of the hangers

13^a are riveted to the agitator 13 by the rivets 13^b. The upper ends of the hangers 13^a are folded upon themselves as shown at 13^c and through the folded portions and the 60 bodies of the hangers the shaft 11 extends. Where the shaft 11 penetrates the folded portions and the bodies of the hangers, it is provided with notches 11^b, to receive the keys 11^c. These keys cause the hangers 13^a 65 to move with the shaft 11 when the same is rocked, and furthermore prevent longitudinal movement of the hangers with relation to the shaft. The length of the agitator substantially fits the width of the receptacle and 70 is designed to swing backward and forward when the handle is manipulated. The agitator is V-shaped in cross section, and is constructed hollow, as shown in the longitudinal sectional view.

75 Arranged in the hollow portion of the agitator is a partition 15, which divides the agitator into two cup compartments 18 and 19. This partition is held in place by the pins 16. The clothes when the agitator is 80 manipulated are partially drawn or sucked into the cup compartments 18 and 19, by virtue of a partial vacuum therein. The partition 15 does not quite extend to the lower edges of the agitator thus permitting 85 the clothes to be drawn between the sides of the agitator below the lower face of the partition. A depression 20 is formed in the partition, which depression performs a function substantially similar to those 90 performed by the cup compartments. To prevent the clothes from being drawn entirely in to the cup compartments, and to allow a space between the clothes and the tops of the cup compartments, wires 21 extend 95 transversely of the lower portions of the cups. The end portions of the rods or wires are formed in loops, with their extremities penetrating the upper side portions of the agitator, as shown at 21^a. These 100 loops 22 are arranged on the sides of the agitator, and constitute supplemental agitating members.

As the pendulum agitator is oscillated the water, suds and the clothes are thrown over the agitating strips or cleats 9, and against one end or the other of the receptacle. As the clothes are thus agitated or manipulated, the hot water and suds percolates through the clothes, and into the cup 110 compartments of the agitator, and as the agitator leaves one end or the other of the

receptacle, moving in the direction of the center of the receptacle, the hot water and suds escapes through the clothes

To operate a machine of this design medium power is necessary.

The invention having been set forth, what is claimed as new and useful is:—

A pendulum agitator, adapted to be suspended within a washing machine inclosure and provided with a handle for oscillating the same; the agitator being elongated, hollow, and substantially V-shaped in cross section, a partition arranged in the hollow portion of the agitator substantially midway of its length, thereby dividing the same into two compartments, said partition being provided with a chamber, and terminating a short distance from the lower edges of the

side of the agitator; a pair of substantially annular split rings, one being arranged transversely of each compartment, and extending through the sides of the agitator, with the ends of each ring penetrating through and secured in the upper portions of the sides of the agitator, and arms secured to each end of the agitator, whereby the agitator may be suspended, said rings constituting supplemental agitating members.

In testimony whereof I have signed my name to this specification in the presence of two subscribing witnesses.

EUGENE ALBERT PALMER.
